STOP MECHANISM FOR LOOMS.

No. 404,407.

Patented June 4, 1889.

UNITED STATES PATENT OFFICE.

EDUARD HERZIG, OF WEST HOBOKEN, ASSIGNOR TO RAND H. SIMON, OF UNION, NEW JERSEY.

STOP MECHANISM FOR LOOMS.

SPECIFICATION forming part of Letters Patent No. 404,407, dated June 4, 1889.

Application filed September 8, 1888. Serial No. 284,903. (No model.)

To all whom it may concern:

Be it known that I, EDUARD HERZIG, a resident of West Hoboken, Hudson county, New Jersey, have invented certain new and useful Improvements in Stop Mechanism for Looms, of which the following is a specification.

The object of my invention is to provide improved means for stopping the loom when the shuttle-thread breaks or when the shuttle sticks in the shed.

The invention consists in the details of improvement and the combinations of parts that will be more fully hereinafter set forth.

Reference is to be had to the accompanying drawings, forming part of this specification, in which—

Figure 1 is a side elevation, partly broken, of a portion of a loom embodying my improvements. Fig. 2 is an enlarged detail view of part of my improvements. Fig. 3 is a detail side view of the parts shown in Fig. 2. Fig. 4 is a detail top view, and Fig. 5 is a detail side view, of the cam for throwing the driving mechanism out of gear. Fig. 6 is a longitudinal sectional view, on an enlarged scale and partly broken, on the line *c c*, Fig. 1, of a portion of the loom, showing some of my improvements in position. Fig. 7 is a partly-broken detail view of the lever for locking the lever that throws the driving mechanism out of gear. Fig. 8 is an enlarged detail view of a portion of my improvements shown in Fig. 1. Fig. 9 is a detail edge view thereof; and Fig. 10 is a detail view of parts shown in Fig. 1, the batten being in the forward position.

In the accompanying drawings, the letter *A* represents the frame of a loom, and *B* is the batten of said loom. *D* is the shuttle-race carried by said batten, and *E* are the heddles of the loom. These parts may be of any approved construction.

F is a bracket that is carried by the batten *B*. In suitable bearings on this bracket is journaled a shaft *a*, that is provided at one end with a fork or fly *G* and at its opposite end with a crank *b*. The crank *b* is connected by a rod or link *d* with a lever *H*, that is pivoted on the batten *B*, as shown in Fig. 1.

e is a spiral spring that surrounds the shaft *a*. Said spring is secured at one end to said shaft, and its other end presses against the bracket *F*, so as to turn the shaft *a* to normally hold the fork *G* in the position shown in Fig. 1, and to also hold the lever *H* depressed, as in said figure. When the batten swings forward to beat up the weft, the free end of the lever *H* will strike a tongue *I*, that is pivoted on a bracket *f*, that projects from the frame *A*.

The tongue *I* is kept in the elevated position by means of a spring *g*, and is limited in its upward movement by an adjustable stop or plate *h²*, carried by the bracket *f*. The plate *h²* has a slot *h³*, through which passes a screw *h⁴*, that enters the bracket *f*, whereby the plate *h²* is made adjustable. By adjusting the stop *h²* up or down the vertical movement of the tongue *I* may be regulated. When the batten swings forward and the lever *H* strikes the tongue *I*, said lever will be raised, thereby turning the shaft *a*, through means of the link *d* and crank *b*, so as to move the fork *G* forward into the position shown in Fig. 10. When in this position, the fork *G* is adapted to engage the shuttle-thread, as hereinafter shown. By making the tongue *I* movable slightly the shock and wear on the lever *H* that would result by its contact with a stationary abutment are avoided.

J is a fork or open frame that is carried by a vertical rod *h*. The rod *h* passes into a pivoted block *i*, that is hung on a support *j*, that is carried by the frame *A*. The fork *G* is adapted, when the batten swings forward, to contact with the fork *J*, or, in other words, the prongs of the fork *G* are adapted to pass into the spaces between the prongs in the fork *J*, as in dotted lines in Fig. 6. The upper end of the rod *h* is guided by a forked rod *l*, carried by the support *j*. The lower end of the rod *h* is connected to a lever *L*, that is pivoted at one end upon a cross-piece *m*, carried by the frame *A*, which lever is adapted to be moved laterally by the rod *h*. The lower end of the rod *h* and the lever *L* are moved toward or against the support *j* by means of a spring *n*, as in Fig. 6. The free end of the lever *L* is adapted to come over

one end of a lever M, the opposite end of which lever M is forked and rests upon a rod o, as in dotted lines in Fig. 1.

N is a rod that passes across the frame A and rests upon the lever M. The rod N is connected to the devices for throwing the driving-gear of the loom out of action. The rod N is notched, as at n in Fig. 6. The rod N passes through a hole p in the frame A, its notch n resting on the metal of the frame A at said hole when the loom is in operation; but when the rod N is raised and its notch disengaged from said metal said rod will be drawn to one side and throw the driving mechanism out of gear, as in ordinary looms. The outer end of the lever M is kept upon the rod o by a spiral spring q, that is connected at one end to said lever and at its opposite end to the frame A. The lever M is connected by a rod r with a lever O, that is pivoted at one end in the frame, and at its opposite end said lever rests upon a cam P, that is carried by a shaft Q, hung in bearings in the frame A and driven by suitable mechanism. The free end of the lever O that contacts with the cam P preferably has a projection, as shown in Fig. 1.

The cam P which I prefer to use is of the construction shown clearly in Fig. 5—that is to say, for a portion of its circumference it is circular, it then has a slightly-raised part s for another portion of its circumference, and at the end of said raised part s it is provided with a projection or tongue t. Above the free end of the lever L is a stop U, that limits the upward movement of the lever M when the lever L is beneath the stop U. The stop U is high enough above the lever L to permit the part s of the cam P to raise the lever M when the lever L is over said lever M; but said stop U prevents the projection t on the cam P from raising the lever M when the lever L is above it, so that the outer end of the lever M will be raised by the cam P.

R is a lever that is pivoted to a support v, carried by the frame A. The pivot w of the lever R passes through a vertical slot x in said lever, within which slot is a spiral spring y, that bears against the pivot w and against the bottom of said slot, which spring acts to keep the lever R depressed, while permitting said lever to have a slight vertical movement. (See Fig. 7.) The upper end of the lever R is adapted to be engaged by the batten B to move the lower end of said lever outward. The lower end of the lever R is adapted to come above the free end of a lever M², that is constructed and operated similarly to the lever M. The lever M² is connected by a rod r² with a lever O², that is acted upon by a cam P², similar to the cam P carried by the shaft Q. The free end of the lever M² is adapted to engage the rod N in manner similar to the lever M. The lever O² is hung in the frame A similarly to the lever O. The cams P and P² are placed upon the shaft Q with their projections facing in opposite directions, as in Fig. 1.

My improvements operate as follows: Suppose the above-described parts to be at the right of the loom and at the right of the cloth 70 being made upon said loom. The shuttle is now thrown from the left to the right and comes to rest in the box D at the end of the batten B. In its passage across the batten the shuttle lays a thread in the shed in the 75 usual way, said thread being laid in line with and between the forks G J. The batten now comes forward to beat up the thread, and as it advances the lever H strikes the tongue I, whereby the lever H will be raised and 80 turn the shaft a and thus swing the fork G down into about the position shown in Fig. 10, thereby drawing the thread a⁴ across the face of the fork J and confining it between said fork and the fork G, as in Fig. 6. As 85 the batten now advances slightly farther the fork G, by pressing the thread a⁴ against the fork J, will carry said fork J backward, thereby moving the lower end of the rod h outward, which carries with it the lever L, 90 thereby moving the free end of said lever from over the free end of the lever M and from beneath the stop U. During the above operations the shaft Q is revolving, and just as the batten comes forward to beat up the 95 thread the part s of the cam P reaches the lever O and raises it slightly, thereby also raising the free ends of the levers M L slightly. When the lever L is now moved outward from the lever M, as stated, it will slip off the 100 end of the lever M, and as said lever M was raised slightly, as stated, the free end of the lever L will be prevented from again coming over the top of the lever M until said lever has been depressed again. As the batten 105 comes forward, as above stated, it also engages the upper end of the lever R, thereby moving the lower end of said lever from over its lever M²; but as the narrow part of the cam P² is in contact with the lever O² at this 110 time the lever M² is not moved by the cam P². Every time the batten comes forward it 115 will move the lever R. While the batten is now returning to its outward position the projection t of the cam P will engage the lever O and raise said lever to its fullest extent, thereby raising the free end of the lever M, which is permitted by the lever L being away from the stop U. When the batten reaches its outward position, the shuttle will 120 be thrown again from the right to the left. As the batten now again advances to beat up the thread it will engage the lever R and move the lower end of said lever outward from over the lever M²; but just before the 125 end of said lever is thus moved outwardly the part s² of the cam P² engages the lever O² to slightly raise said latter lever, and with it the levers M² and R, so that as the lever R is moved from the lever M² by the batten, as 130 stated, it will be depressed by the spring y, and will be prevented from coming over the lever M² by said lever being in its way. As the shaft Q still rotates the projection t² on the

cam P^2 will raise the lever O^2 , and thereby the lever M^2 , to its fullest extent. The batten now having moved outwardly again, the shuttle is thrown back, as before, to cross the 5 path of the forks $G J$. Each time the batten comes forward and the shuttle is on the right-hand side of the batten its thread will engage the fork J to move the lever L outward to permit the free motion of the lever M , while when the shuttle is at the left of the batten the lever R will be moved outward to permit free movement of the lever M^2 , the 10 cams $P P^2$ alternately moving the levers $O O^2$, one for each stroke of the batten. If, 15 now, the shuttle is thrown to the right, but for some reason the thread does not cross the face of the fork J to be pushed against said fork by the fork G —for instance, if the shuttle sticks in the shed, or if the thread breaks, or the 20 cop becomes empty, so that no thread will be drawn across in front of the fork J —the lever L will be left over the lever M , because there is now no thread to move the fork J , and as the cam P rotates and its projection t engages 25 the lever O and raises said lever to its fullest extent the inner end of the lever M , being held down by the lever L and stop U , will cause the free or outer end of the lever M , that is beneath the rod N , to be raised by the 30 rod r , whereby instantly the rod N will be thrown to disengage the actuating mechanism, and thereby the loom be stopped. The mechanism shown in my former patent, No. 308,359, November 25, 1884, may be used for 35 stopping the loom upon the disengagement of rod N . If, on the other hand, the shuttle be thrown toward the left and it should stick in the shed and prevent the forward motion of the batten, the lever R , by not 40 being moved away from the end of the lever M^2 , will prevent the raising of said end of said lever M^2 by the cam P^2 , and thereby the opposite end of said lever will be raised by the cam P^2 when its projection t^2 engages 45 the lever O^2 , thereby raising the rod N through the lever M^2 , which immediately acts to disengage the actuating mechanism of the loom. The batten may be actuated by hand by the means shown in United States 50 Patent No. 286,081, dated October 2, 1883, or otherwise.

From the above construction it will be seen that the forks $G J$ and the lever R act alternately to disengage the actuating mechanism—that is to say, if the shuttle should have arrived with its thread at the right or at the side of the loom at which the fork J is situated the forks $G J$, with the thread a^4 , will act to move the lever L away from the lever 55 M and permit free movement of the latter lever; but if said thread does not come between said forks the lever L will remain between the lever M and stop U , and thereby the cam P will be permitted, through the lever $O M$, to stop the actuating devices; also, 60 that if the shuttle should be thrown to the

left, or at the side opposite the forks $G J$, and should stick in the shed and prevent the forward swing of the batten, the lever R will remain over its lever M^2 , so that the cam P^2 70 will act to throw the rod N to stop the actuating mechanism of the loom.

Having now described my invention, what I claim is—

1. In a loom, the batten B and the movable 75 fly or fork G carried by said batten, and means, substantially as described, for actuating the fork G , combined with the fork J , a pivoted support carrying said fork, lever L , lever M , a cam or eccentric for actuating the 80 lever M , devices intermediate said cam and lever, and a device operated by the lever M to stop the loom, substantially as set forth.

2. In a loom, the batten B , bracket F carried thereby, fly or fork G , carried by the 85 bracket F , and lever H , carried by the batten above the fly G and connected with the fly or fork G , in combination with the stop or tongue I , and support f , carrying said tongue, said stop or tongue being above the fly or fork G , 90 substantially as described.

3. In a loom, the batten B , bracket F , shaft a on said bracket, fly or fork G and crank b on said shaft, lever H , and link d , said lever being above the fly or fork G , combined with 95 the tongue I , and support f , carrying said tongue, said tongue being above the fly or fork G , substantially as described.

4. In a loom, the batten B , bracket F , shaft a , fly or fork G and crank b on said shaft, 100 lever H , and link d , combined with the tongue I , and support f , carrying said tongue, and with the fork J , lever h , levers L and M , a cam or eccentric for actuating the lever M , devices intermediate said cam and lever, and 105 a device operated by the lever M to stop the loom, substantially as described.

5. The batten B and the swinging fly or fork G carried thereby, and means, substantially as described, for actuating the fork G , 110 combined with the fork J , lever h , levers L M , stop U , rod N , connected with the driving-gear, rod r , lever O , and cam P , all arranged for operation substantially as herein shown and described. 115

6. In a loom, the batten B , combined with the lever R , having a slight vertical movement, lever M^2 , a cam or eccentric for actuating the lever M^2 , devices intermediate said cam and lever M^2 , and a device operated by 120 the lever M^2 to stop the loom, as specified.

7. In a loom, the batten B , combined with the lever R , having opening x , pivot w , passing through said opening and carried by the support v , support v , spring y , lever M^2 , a 125 cam or eccentric for actuating said lever, devices intermediate said cam and lever M^2 , and devices operated by the lever M^2 to stop the loom, as specified.

8. In a loom, the batten B , combined with 130 the lever R , having a slight longitudinal movement, lever M^2 , rod N , connected with the

driving-gear, rod r^2 , lever O^2 , and cam P^2 , all arranged for operation substantially as herein shown and described.

9. The batten B , bracket F , fork G , and 5 lever H , connected to the fork and carried above the fly or fork G , combined with the tongue I , spring g , supporting the free end of

said tongue, and support f , substantially as described.

EDUARD HERZIG.

It is hereby certified that in Letters Patent No. 404,407, granted June 4, 1889, upon the application of Eduard Herzig, of West Hoboken, New Jersey, for an improvement in "Stop Mechanism for Looms," the name of the assignee was erroneously written and printed "Rand H. Simon," whereas said name should have been written and printed *R. and H. Simon*; that the proper correction has been made in the files and records pertaining to the case in the Patent Office, and should be read in the Letters Patent to make the same conform thereto.

Signed, countersigned, and sealed this 25th day of June, A. D. 1889.
